[57] CLAIM

The ornamental design for the combined storage and display device for graphic pictures or the like, as shown and described.

DESCRIPTION

FIG. 1 is a top plan view of a combined storage and display device for graphic pictures or the like showing our new design;

FIG. 2 is a perspective view of FIG. 1;

FIG. 3 is a top plan view of a second embodiment of the design of FIG. 1;

FIG. 4 is a perspective view of FIG. 3.

FIG. 1

FIG. 3

FIG. 2

FIG. 4
